PORTABLE TOILET DEVICE

Ernest Nagel and Stellane Nagel, Downey, Calif.

Application November 3, 1955, Serial No. 544,728

3 Claims. (Cl. 4—135)

This invention relates generally to toilet devices and relates more particularly to portable toilets for small children.

It is an object of the invention to provide a portable toilet that is particularly adapted for easy and convenient use by small children.

Another object of the invention is to provide a device of this character wherein the lower part is unitary in construction with the pot a part of the base, or lower section or part.

Still another object of the invention is to provide a device of this character wherein there is novel means for sealingly securing the pot lid in closed position.

A further object of the invention is to provide a device of this character wherein the pot lid may be easily and quickly released for removal so that the device may be used.

A still further object of the invention is to provide a device of this character that has a back member for supporting the back of a child using the device, said back member being part of the lower section or part of the device.

Another object of the invention is to provide a device of this character that is easy to handle for emptying, or the like.

Still another object of the invention is to provide a device of this character that has a protective cover which encloses the lower part.

A further object of the invention is to provide a device of this character having novel means for securing the cover to the lower part of the device.

Still another object of the invention is to provide a device of this character that is simple and sturdy in construction.

Another object of the invention is to provide a device of this character that is relatively inexpensive to manufacture.

The characteristics and advantages of the invention are further sufficiently referred to in connection with the following detailed description of the accompanying drawings which represent one embodiment of the device. After considering this example, skilled persons will understand that many variations may be made without departing from the principles disclosed and we contemplate the employment of any structures, arrangements or modes of operation that are properly within the scope of the appended claims.

Referring to the drawings:

Fig. 1 is a plan view of the device with the cover attached;

Fig. 2 is a vertical section taken on line 2—2 of Fig. 1;

Fig. 3 is a cross section taken on line 3—3 of Fig. 2;

Fig. 4 is a front elevation of the lower part or section of the device;

Fig. 5 is a sectional view of the releasable lid securing means taken on line 5—5 of Fig. 3;

2

Fig. 6 is a sectional view taken on line 6—6 of Fig. 5; and

Fig. 7 is a sectional view of the cover securing means taken on line 7—7 of Fig. 3.

Referring more particularly to the drawings, the device may be of suitable plastic material or any other suitable material, and comprises a lower part or section, indicated generally at 10, and a cover or top section, indicated generally at 12.

10 The lower section comprises a base 14, shown as circular in shape, having a thickened portion 15 from the periphery of which is an upstanding wall 16 having a rear part 17 generally semi-circular in cross section and a front part 18 generally semi-ovate. A flange 19 extends from the upper edge of the wall 16 outwardly, the rear part 20 of said flange being arcuate in shape and the forward part 21 being of generally the shape of half an oval or semi-ovate.

20 The upper interior edge of the wall of the pot is beveled or rounded, as at 23, and receives the thickened portion 24 of a lid, indicated generally at 25, which has a flange 26 extending outwardly about the portion 24. A gasket 27 is provided on the under side of the flange 26 for sealing engagement with the top surface of the

25 pot flange 19. Means for releasably securing the lid is provided, and comprises a pair of latch devices, indicated generally at 30, one at each side of the lid. As the latch devices 30 are of the same construction and operation, a description of only one will be made.

30 Each latch device 30 comprises a vertical rod 31, having its lower end portion slidably received in the bore 32 of a boss 33 upstanding from the base 14 in outwardly spaced relation to the wall 16 of the pot. The boss 33 may be formed integrally with the base or secured thereto by any suitable means, such as an adhesive, screws or the like. The upper end of the rod 31 extends upwardly through and is slidable in an opening 35 provided therefor in the flange 19 and at the upper end of said rod is a laterally turned cover engaging projection or hook 36. The opening 35 is provided with a laterally extending part 37 into which the hook 36 fits when the rod is in the downward or retracted position, at which time the lower end of the rod rests on the bottom of the recess or bore 32 and the top end of the rod and hook are substantially flush with the upper surface of the flange 19 so that the upper surface of the device will be smooth and devoid of upwardly projecting parts when the device is in use. There is also a spring 39 about the upper end of the rod, said spring reacting between the under side of the flange 19 and a cross pin 40 received in a cross bore provided therefor in said rod, said spring yieldingly urging the rod downwardly.

45 In assembling the latching device, the rod 30 is inserted in the opening 35 and the spring 39 placed on said rod. The lower end of the rod is then placed in the bore 32, the spring being compressed against the flange 19 sufficiently to permit insertion of the cross pin 40.

55 It is to be noted that the openings 35 are adjacent the edge of the lid at substantially opposite sides thereof and are not covered by the edge portion of said lid. Also, the portions 37 of the openings 35 also are clear of the lid so that when the hooks 36 are within the portions 37 the rods may be raised and the hooks turned toward the lid and overlie adjacent edge portions of said lid. The springs 39 urge the rods downwardly to securely press the lid down and hold it in sealing engagement with the flange 19.

60 The lid is provided with a handle 42 so that it may be easily removed when released from the latching means, said release being effected by raising the rods slightly and

turning same to a position whereat the hooks are clear of the lid and will enter the portions 37 when lowered.

The pot portion of the lower section or part is forwardly off-set or off center of the base to provide room for a pot handle 44 at the rear of the pot, and said handle may extend vertically between the base 14 and the flange 19. There is also an arcuate back supporting member 49 upstanding from the flange 19 at the rear thereof.

The cover may be of any suitable shape but is shown as cylindrical, having a cylindrical wall 50 and a top wall 51. The cover is adapted to fit over the lower section and rest on the outer edge portion of the base, although it may be otherwise arranged. In any event the pot, handle 44 and back member 49 may, if desired, be formed integrally.

There is also means for securing the cover to the lower section, said means including arcuate members 52 having depending end portions 53 secured to the base so that the members 52 are spaced upwardly of the base and define with portions thereof, openings 55 for reception of downwardly tapered inner end portions 56 of pins 57 which are slidable in openings provided therefor in lugs 58 at the lower end of the cylindrical wall 50 of the cover. The arrangement is such that the cover may be secured by the pins 57 without having to be exactly placed on the lower section, said openings 55 extending horizontally. Obviously the pins 57 will enter any part of said slots or openings 55 and engage the members 52 to secure the cover to the lower part of the device. The pins 57 are at generally opposite sides of the device although they do not need to be exactly opposite. If desired the outer ends of the pins may be provided with cross-pins 57a.

The cover is also provided with a compartment 60 in the upper forward portion, as best shown in Fig. 2. The compartment is defined by walls 61 and said compartment may be used for storage of toilet paper or any other articles that may be needed and will fit into said compartment. The top 51 of the cover defines only a portion of the upper end of said cover, the remaining portion comprising a closure wall 63 hinged at 64 along its chordal edge which lies adjacent the chordal edge 65 of the top 51. A handle 66 is secured to the top 51 for lifting and carrying the device when the cover is attached, and for removing or replacing the cover.

The device is compact and convenient and may be used in an automobile when traveling, or in the home. Further, it is thought that the invention and many more of its attendant advantages will be understood from the foregoing description and it is thought that it will be apparent that various changes may be made in the form, construction and arrangement of the parts thereof without departing from the spirit and scope thereof, or sacrificing all of its material advantages, the form hereinbefore described being merely an example of one embodiment.

We claim:

1. A device of the character described, comprising: a base having a wall upstanding therefrom to define, with a portion of said base, a pot chamber offset forwardly on said base, said chamber wall curving forwardly and inwardly; a flange extending horizontally outwardly from the upper edge of the chamber wall and having openings therethrough at generally opposite sides of said chamber and spaced outwardly of said chamber; a removable lid for said chamber, having a horizontal marginal portion extending outwardly of said chamber to a position adjacent to but short of said openings; a marginal gasket on the lower side of said lid; guide means extending upwardly of the base beneath each of said openings and each guide means having a vertical recess aligned with its respective opening; each opening having a vertical rod slidable there-

in, said rod having its lower end loosely slidable in the bore of the respective guide means, said rod having a laterally extending hood adapted to be received in a portion of the opening when the rod is in its lower position at which time the upper end of said rod is substantially flush with the upper surface of the flange about the upper end of said chamber and the lower end of said rod rests on the bottom of said bore; yielding means urging said rods to the lower position, said rods being adapted to be raised and rotated to bring the hooks into overlying position relative to adjacent marginal portions of said lid so that said lid is held down by said yielding means; a back member upstanding from said flange behind said chamber; a handle on said chamber at the rear thereof; a cover adapted to cover said chamber, back and handle; a storage compartment in the upper forward portion of said cover; an openable closure for said compartment; and means for releasably securing said cover to said base, including means defining elongated horizontal openings, and pins slidable in openings provided therefor in the cover, said pins being receivable in said elongated openings.

2. A device of the character described, comprising: a base having a wall upstanding therefrom to define, with a portion of said base, a pot chamber offset forwardly on said base, said chamber wall curving forwardly and inwardly; a flange extending horizontally outwardly from the upper edge of the chamber wall and having openings at generally opposite sides of said chamber and spaced outwardly of said chamber; a removable lid for said chamber, having a marginal portion extending outwardly; a marginal gasket on the lower side of said lid; vertical rods slidable in said openings and having hook portions at the upper ends; guides for the lower ends of said rods; yielding means urging said rods downwardly, said rods being rotatable to move said hooks between a position overlying edge portions of said lid and a position clear of said edge portions; a back member extending upwardly from the flange at the rear of the chamber; and a handle on said chamber wall at the rear thereof.

3. A device of the character described, comprising: a base having a wall upstanding therefrom to define, with a portion of said base, a pot chamber offset forwardly on said base, said chamber wall curving forwardly and inwardly; a flange extending horizontally outwardly from the upper edge of the chamber wall and having openings at generally opposite sides of said chamber and spaced outwardly of said chamber; a removable lid for said chamber, having a marginal portion extending outwardly; a marginal gasket on the lower side of said lid; vertical rods slidable in said openings and having hook portions at the upper ends; guides for the lower ends of said rods; yielding means urging said rods downwardly, said rods being rotatable to move said hooks between a position overlying edge portions of said lid and a position clear of said edge portions; and a back member extending upwardly from the flange at the rear of the chamber.
